UNITED STATES PATENT OFFICE

WALTER D. HODSON, OF MARION, INDIANA, ASSIGNOR TO BENJAMIN F. BURK AND PHILIP MATTER, COPARTNERS AS FIRM OF NATIONAL SWEEPER COMPANY, OF MARION, INDIANA.

ROLLER-BEARING.

No. 848,650.

Specification of Letters Patent.

Patented April 2, 1907.

Application filed June 22, 1903. Serial No. 162,492.

To all whom it may concern:

Be it known that I, WALTER D. HODSON, a citizen of the United States, residing at Marion, in the county of Grant and State of Indiana, have invented a certain new and useful Improvement in Roller-Bearings, of which the following is a specification.

My invention relates to roller-bearings, and has for its object to provide particularly for use in connection with carpet-sweepers and the like a roller-bearing in which there shall be a relatively small bearing-surface for the roller.

The invention is illustrated in the accompanying drawings, wherein—

Figure 1 is an elevation of one of the rollers; Fig. 2, a longitudinal section through the casing with the rollers removed, and Fig. 3 a cross-section through the casing at right angles to the plane of Fig. 2.

Like parts are indicated by like letters in all the figures.

A is a cup case or cylinder preferably having the perforated removable cap B, receiving the shaft C through its perforation.

D is a retainer or spacer which can be used to hold the rollers together. It is, in effect, an annulus with the exterior notches E E to receive the rollers. The retainer is centrally perforated to permit the shaft to pass therethrough. The rollers consist of the flexible rods or shafts L, carrying at each end the balls or rollers K K. The shafts are notched at F, the place of their engagement with the retainer or spacer D.

35 I claim—

In a roller-bearing, the combination of a retaining-case with a plurality of roller-like parts each comprising a pair of spherical bearing devices, one at each end of the case, a flexible connection between such devices, and a spacer comprising an annulus having notches to receive the several flexible connections of the bearing device, said annulus being arranged centrally of the casing to keep the roller-like parts in position.

40 WALTER D. HODSON.
